By J. W. Bond

ATTORNEY

UNITED STATES PATENT OFFICE.

DAVID ELEY, OF FUNK, OHIO.

LIFTING-JACK.

1,272,237.

Specification of Letters Patent.

Patented July 9, 1918.

Application filed February 6, 1918. Serial No. 215,582.

To all whom it may concern:

Be it known that I, DAVID ELEY, a citizen of the United States, residing at Funk, in the county of Wayne and State of Ohio, 5 have invented a new and useful Lifting-Jack, of which the following is a specification.

This invention relates to lifting jacks, the object being to construct a simple, inexpensive and durable device of this kind with 10 means for positively reversing the direction of movement of the lifting bar of the said jack.

Another object is to construct a jack in 15 which the several parts can be assembled and disassembled without the use of tools.

With these objects in view the invention consists in the novel construction and arrangement of parts, hereinafter described, 20 illustrated in the accompanying drawings, and particularly pointed out in the appended claims, it being understood that various changes in the form, proportions, size and minor details of construction may be made 25 within the scope of the appended claims, without departing from the spirit or sacrificing any of the advantages of the invention.

In the drawings:

30 Fig. 1 is a side elevation of my jack of the side opposite the one to which the operating handle is connected.

Fig. 2 is a vertical transverse sectional view with a part of the operating lever broken away and showing the pawls and co-operating spring in position for lifting.

Fig. 3 is a horizontal section taken on the line 3—3, of Fig. 2.

Fig. 4 is a view similar to Fig. 2, but with 40 the pawls and their co-operating spring in position for lowering.

Fig. 5 is a detail perspective of the lever member.

Fig. 6 is a detail perspective of one of 45 the pawls.

Fig. 7 is a detail sectional view on line 7—7, Fig. 2.

Similar numerals of reference indicate 50 corresponding parts throughout the several figures of the drawing.

The base member or standard 1 of my jack is composed of a single casting and has an off-set portion 2 at one side as clearly shown in Fig. 1. A horizontal opening 3 is 55 formed through the side walls of the casting and in approximately the center of the

main portion of the casting 1 and extending for its entire height is a vertical rectangular slot 4 in which is designed to slide the rack bar 5. A series of teeth 6 and 7 are formed 60 on the rack bar 5 upon its right and left sides respectively, the said series of teeth 6 being arranged in staggered relation to the series of teeth 7 upon the opposite side of the bar. A lever member 8 is bifurcated as 65 shown in Fig. 5 to form arms 9 and 10. Formed in the off-set portion 2 of the casting at approximately the vertical and horizontal center thereof is a round aperture 11 which is adapted to receive a stud 12 formed 70 upon the member 10 of the lever and at a point in direct horizontal alinement with the stud 12 is a round aperture 14 in the member 9, which is adapted to receive a stud 15 carried by the outside of the casting 75 1. The studs 12 and 15 co-operating with the apertures 11 and 14 form a pivot for the lever 8 upon which the said lever is adapted to be rocked. Horizontally alined apertures 16 drilled through the bars 9 and 80 10 at a point adjacent the free ends are adapted to receive a pin 17 upon which is mounted an engaging pawl 18. The upper end of the said pawl is widened to form a shoulder 19, which shoulder is spaced 85 slightly above the upper face of the arm 10 and is of approximately the width of the said arm. Opposite the apertures 16 and spaced the same distance from the stud 12 is a pair of apertures 20 in the arms 9 and 90 10, which apertures receive a pin 21 which carries a pawl 22 similar to the pawl 18, but with its shoulder 24 upon the opposite side of the pawl to the shoulder 19 upon the pawl 18 and it will therefore be seen that each of 95 the shoulders 19 and 24 extends over the arm 10. A tail portion 25 is formed on each of the pawls and is for a purpose herein-after to be set forth. It will be noted that the pawls are mounted upon the pins 16 and 21 in such a way that the constant tendency of the upper or engaging portion of each pawl is to fall inwardly toward the bar 5. A lug 26 formed integral upon the upper 100 side of the lever 8 is slotted to receive a leaf spring 27, which spring extends along the face of the lever 8 and over a pin 28 set in a lug 29, the said pin is cut away for half its diameter as at 30, and is adapted to be semi-rotated within the lug 29 by means of 105 an operating finger 31. An opening 32 is formed in the end of the lever 8 and is 110

adapted to receive a handle 34 to give an increased leverage in operating the jack.

In assembling my jack the arm 10 is inserted through the opening 3 until the stud 5 12 on the arm 10 and the aperture 14 in the arm 9 have come into register with the aperture 11 and stud 15 respectively when the lever portion 8 is moved sidewise inserting the stud 12 in the aperture 11 and the stud 10 15 in the aperture 14. The bar 5 is then inserted from the top, thus preventing the arms 9 and 10 from moving to withdraw the studs from their respective apertures. The pawls 18 and 22 are then positioned 15 between the arms 9 and 10 and the pins 17 and 21 inserted and secured by cotter pins. It is thus seen that no tools are necessary to assemble the several parts of my jack and the disassembling may be accomplished by 20 withdrawing the cotter pins, removing the pawls and rack bar and sliding the lever member 8 sidewise to withdraw the studs from their respective apertures. In Fig. 2 I have shown the several parts of my jack 25 in position to force the rack bar upwardly to lift when the lever member 8 is oscillated vertically by the handle 34. As the handle 34 reaches the limit of its downward movement the pawl 22 will be in position to drop 30 under one of the teeth 6 and as the handle 34 is then moved upwardly the engagement of the pawl 22 with the said tooth will move the rack bar 5 upwardly the distance of one tooth. In the meanwhile the pawl 18 is being carried downwardly and as the handle 34 reaches the limit of its upward movement the said pawl 18 will be in position to drop 35 under one of the teeth 7. It is thus seen that at each upward or downward stroke of the 40 handle, the rack bar 5 is moved upwardly to lift the load.

Referring now to Fig. 4 the parts are seen in position to lower the rack bar 5. The operating finger 31 has been thrown to the 45 opposite side of the pin 28 to the side which it occupies in Figs. 2 and 3, the rounded end of the said pin 28 being now turned uppermost thus forcing the leaf spring 27 to exert a pressure against the shoulders 19 and 21 50 of the pawls 18 and 22. The said pressure against the shoulders of the pawls by the spring 27 causes the upper ends of the said pawls to be swung away from the rack bar, the tail portions 25 upon the pawls contacting 55 with the rack bar 5 to limit the distance which the said upper portions will be spaced from the said rack bar. Just before the handle 34 reaches the limit of its upward movement the upper end of the pawl 22 60 will be swung into engagement with one of the teeth 6 and as the handle travels the last fraction of an inch upwardly the rack bar 5 will be lifted slightly allowing the spring to throw the pawl 18 out of engagement with 65 whichever one of the teeth 7 it was en-

gaged on its last stroke. As the handle begins its downward travel the pawl 22 will remain in engagement with the tooth 6 which it engaged at the end of its upward stroke, thus lowering the rack bar 5 the distance of one tooth. The pawl 22 will remain in engagement with the said tooth until the handle has reached nearly the limit of its downward travel when the pawl 18, which is now moving upwardly will have engaged 75 one of the teeth 7 and as the handle 34 travels the remaining fraction of an inch, until it reaches the limit of its downward movement, the pawl 18 will lift the rack bar slightly allowing the spring to disengage 80 the pawl 22 from the tooth which it was engaging. It will thus be seen that at each stroke of the handle 34 the pawl 5 is dropped a notch to lower the load.

Having fully described my invention, 85 what I claim as new and desire to secure by Letters Patent, is—

1. In a lifting jack, a standard, an off-set portion formed upon said standard, a horizontal aperture formed through said standard at the point where said off-set occurs, a relatively smaller horizontal aperture formed in said off-set portion at right angles to said first aperture and a stud carried upon the outside of said standard at a point 90 in horizontal alinement with said second aperture, a bifurcated lever, a stud carried by one of the bifurcations of said lever, an aperture formed in the other of said bifurcations and in horizontal alinement with the said stud carried by the said first mentioned bifurcation, said first mentioned bifurcation being adapted to be inserted through the said horizontal aperture in the said standard and to be moved sidewise to 95 cause the stud upon the said first named bifurcation to enter the aperture in the said off-set portion and to simultaneously cause the stud carried by said standard to enter the aperture in said second named bifurcation, a vertical passage through said standard, a lifting bar adapted to fit within the said passage when said lever has been positioned and to lock said lever against removal from said standard. 110

2. In a lifting jack, a standard, a lifting bar adapted to slide vertically within said standard, a lever fulcrumed upon said standard, a pawl mounted upon said lever at either side of said fulcrum and equi-distant 120 therefrom, a series of ratchet teeth upon one side of said lifting bar adapted to be engaged by one of the said pawls and a series of ratchet teeth upon the opposite side of said lifting bar and arranged in staggered 125 relation with said first series of said ratchet teeth and adapted to be engaged by the other of said pawls, the said pawls and their respective series of ratchet teeth upon the said lifting bar being adapted to coact to 130

force the said lifting bar upwardly when the lever is oscillated vertically upon its fulcrum, a spring carried by the said lever, the said spring being normally adapted to lie out of engagement with the said pawls and means carried by the said lever for forcing the said spring into engagement with the pawls to cause the said pawls to co-act with their relative series of ratchet teeth to lower the lifting bar when the lever is oscillated vertically upon its fulcrum. 10

In testimony that I claim the above, I have hereunto subscribed my name.

DAVID ELEY.
